CLAIM

The ornamental design for sling chair body, as shown
and described.

DESCRIPTION

FIG. 1 is a front perspective view of a sling chair body
embodying my new design.

FIG. 2 is a top plan view of the sling chair body shown
in FIG. 1.

FIG. 3 is a side elevation of the sling chair body as
shown in FIG. 2.

FIG. 4 is an enlarged fragmentary section of the sling
chair body taken at 4—4 in FIG. 2.
